UNITED STATES PATENT OFFICE.

EDWARD MANES, OF GOLDEN, ILLINOIS.

PNEUMATIC-HAMMER MUFFLER.

1,115,704.

Specification of Letters Patent.

Patented Nov. 3, 1914.

Application filed December 23, 1913. Serial No. 808,445.

To all whom it may concern:

Be it known that I, EDWARD MANES, a citizen of the United States, residing at Golden, in the county of Adams and State of Illinois, have invented certain new and useful Improvements in Pneumatic-Hammer Mufflers; and I do hereby declare the following to be a full, clear, and exact description of the invention, such as will enable others skilled in the art to which it appertains to make and use the same.

The present invention is directed to pneumatic hammers, and more particularly to a muffler therefor.

15 The invention has for its object to so construct a pneumatic hammer that the exhaust of air, during the operation thereof is muffled to eliminate the objectionable sound characteristic in devices of this character.

20 A further object of the invention is to provide a device of this character which is in the nature of an attachment which can be applied to hammers of conventional form.

With these and other objects in view, this 25 invention resides in the novel features of construction, formation, combination and arrangement of parts to be hereinafter more fully described, claimed and illustrated in the accompanying drawing, in which:—

30 Figure 1 is a perspective view of a hammer equipped with the device. Fig. 2 is a longitudinal sectional view therethrough. Fig. 3 is a transverse sectional view.

Referring to the drawing, the numeral 1 35 designates the hammer having the usual casing 1' in which operates the usual hammer 2 adapted for reciprocation therein upon entrance of air which exhausts in the usual manner through the ports 3 and 4.

40 The muffler comprises a sleeve 5 having an annular internal bead 6 which engages the annular shoulder 7 formed upon the hammer casing, so as to prevent displacement of the sleeve 5. A second sleeve 8 is 45 provided, and has one end adapted to telescopically receive the unbeaded end of the sleeve 5, said second sleeve terminating at one end in an annular inclined flange 9.

The muffler further consists of a leather casing 10, which is formed from a single sheet of leather laced at its meeting edges, as indicated at 11, said leather casing being tapered and having its minor end provided with a plurality of perforations 12, which will permit the air to exhaust therethrough. 55

Located in the minor end of the casing 11 is a nipple 13, which is designed to engage the usual extension 14 of the hammer casing, said nipple having connected to one end the rubber tubing 15 which is connected in 60 any suitable manner to the source of air supply.

By providing the bead 6 it will be noted that the sleeves 5 and 8 will be held spaced from the hammer casing, thus locking the 65 exhaust pipe which passes through the ports 3 and 4 and finally through the port 16 and passing into the leather casing 9, which is packed with suitable fabric or waste 17, thereby muffling the air as it exhausts. 70

What is claimed is:—

1. In combination with a pneumatic hammer comprising the usual hammer casing, a muffler comprising a sleeve adapted to inclose the casing, a casing of flexible material 75 inclosing the sleeve, said casing being filled with fabric, and having perforations formed therein to permit the air to exhaust therethrough after passing through the fabric, and means passable through the last named 80 casing to furnish air to the hammer casing.

2. The combination with a pneumatic hammer comprising a casing, of a muffler including a sleeve inclosing the casing, a casing inclosing the sleeve, fabric in said 85 casing and means passing through the last named casing to furnish air to the hammer casing.

In testimony whereof, I affix my signature, in the presence of two witnesses.

EDWARD MANES.
